Patented June 8, 1915.

UNITED STATES PATENT OFFICE.

EDITH WIMMER, OF LOVELAND, AND JOHN SEE, OF STEAMBOAT SPRINGS, COLORADO.

MARKING-GAGE AND TRY-SQUARE.

1,142,215.

Specification of Letters Patent.

Patented June 8, 1915.

Application filed August 21, 1914. Serial No. 857,897.

To all whom it may concern:

Be it known that we, EDITH WIMMER and JOHN SEE, citizens of the United States, residing, respectively, at Loveland and 5 Steamboat Springs, in the counties of Larimer and Routt, State of Colorado, have invented a new and useful Marking-Gage and Try-Square, of which the following is a specification.

10 The present invention appertains to a marking gage and try square, and provides a novel and improved tool or implement of that nature.

15 The present invention contemplates the provision in a device of the character indicated, of a peculiar stock for properly guiding the device along the edge of a board or other object, in combination with an arm assembled with the stock in a peculiar manner to be adjusted transversely thereof, whereby the utility of the implement is enhanced.

20 It is also within the scope of the invention to improve generally devices of the character to which the present invention relates, whereby the same will be comparatively simple, compact and inexpensive in construction, as well as being serviceable, practical and efficient in its use.

25 30 With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

35 40 The invention has been illustrated in its preferred embodiment in the accompanying drawing, wherein—

Figure 1 is a plan view of the improved implement. Fig. 2 is a side elevation thereof. Fig. 3 is a sectional view taken on the line 3—3 of Fig. 2, the arm being shown in full.

45 50 In carrying out the present invention, there is provided an angular stock 1 having the flanges 2 and 3 arranged at right angles with respect to one another, and adapted to engage over one corner of a board or other object, with the flange 3 resting against the edge of the board, and with the flange 2 55 resting upon the top or upper surface of the

board. In this manner, the stock 1 is adapted to be slid in a convenient manner along the edge or side of the board.

The upper flange 2 is provided with a transverse dove-tailed groove or slot 4, 60 through which is slidable an arm or bar 5 of dove-tailed cross section, it being noted that the arm or beam 5 may be adjusted longitudinally of itself through the grooved channel 4, but is constrained against displacement in any other direction unless the arm is withdrawn from the groove 4 to separate the stock and arm. The arm 5 is provided with a longitudinal series of graduations 6 upon its upper face, and the upper 65 face of the flange 2 of the stock is provided with a pointer 7 coöperable with the graduations 6 for indicating the position of the arm 5 with respect to the stock.

70 75 That end of the arm 5 which projects beyond the free edge of the flange 2, is provided with an opening or aperture 8, through which a pencil or other marking element 9 is inserted, and said end of the arm 5 is provided with a slit or slot 10 extending from the opening or aperture 8, and providing a pair of yieldable portions 11 which are engaged by a clamping screw 12, in order that when the clamping screw is tightened, the pencil or marking element 9 80 85 will be clamped within the aperture or opening 8. Thus, when the screw 12 is loosened, the marking element 9 may be removed or adjusted vertically, as desired, the distance of the marking element 9 from the inner face 90 95 of the flange 3 being indicated by the pointer 7 upon the scale of graduations 6.

In order to clamp the arm 5 at any position to which it is set, a transverse thumb piece 13 is provided upon the flange 2 adjacent the groove 4, and has a screw 14 threaded into the stock 1, whereby the ends of the thumb piece 13 are adapted to move over and engage the arm 5 when the screw 14 is tightened by rotating the thumb piece. 100 Thus, when the thumb piece 13 is rotated, to tighten the screw 14, the ends of the thumb piece 13 are adapted to bear upon the arm or beam 5 and the stock for clamping the said arm within the groove 4, and when the screw 14 is unscrewed, the arm 5 will be released in order that it may be adjusted transversely of the stock 1.

The flanges 2 and 3 of the stock 1 are beveled at one end, as at 15, in order to pro- 110

vide a miter square, for marking off angles upon the surfaces to which the stock 1 is applied.

The present implement or tool is particularly adapted for use in manual training, or by carpenters or similar artisans. The angular stock 1 enables the same to be readily and properly applied to the edge or side of a board, and by adjusting the arm 5 with respect to the stock, the marking element 9 may be properly adjusted from the edge of the board through the medium of the pointer 7 and the graduations 6. Then, by running the stock 1 along the edge of the board the marking element 9 will make a line upon the board parallel with and at a predetermined distance from the edge of the board. In a like manner, by readjusting the arm 5, parallel lines may be drawn upon the board, according to the work being done.

The present device may also be employed as a try-square since the arm 5 is disposed at right angles to the stock 1, and furthermore the beveled ends 15 of the flanges 2 and 3 will enable the implement to be employed as a bevel square, to increase the utility of the device. The other advantages and capabilities of the present invention will be obvious from the foregoing, taken in connection with the drawing, without extensive comment being necessary.

In order that the marking element 9 may be set within the free edge of the relatively wide flange 2, the said flange is provided with a transverse open slot 16 below the groove or channel 4 and extending to the flange 3 for receiving the pointed end of the marking element when the marking element

approaches the flange 3. The marking element 9 may thus even be adjusted to a position adjacent the flange 3, when the line is to be marked adjacent the edge of the board, and without destroying the utility of the device. The open slot 16 is narrower than the groove or channel 4, to avoid the flexing of the arm 5.

Having thus described the invention, what is claimed as new is:

1. In a device of the character described, a stock having a channel, an arm slidably through the said channel, and a screw threaded into the stock and having a transverse thumb piece having its ends adapted to bear upon the arm and stock to bind the arm within the channel.

2. In a device of the character described, an angular stock having flanges, and an arm slidably engaged to one flange of the stock and having means for carrying a marking element, the said flange of the stock being relatively wide and having an open transverse slot extending to the other flange for receiving the marking element.

In testimony that we claim the foregoing as our own, we have hereto affixed our signatures in the presence of two witnesses.

EDITH WIMMER.
JOHN SEE.

Witnesses to the signature of Edith Wimmer:

WM. D. DOBBIN,
W. D. WILSON.

Witnesses to the signature of John See:

ADELINE FIELDS,
JAMES F. MCKINNIS.
